[57] CLAIM

The ornamental design for a combined screwdriver bit and sheet metal cutting element for a combination hand tool, as shown and described.

DESCRIPTION

FIG. 1 is a perspective view of a combined screwdriver bit and sheet metal cutting element for a combination hand tool showing my new design;

FIG. 2 is a top plan view thereof, the bottom view being identical;

FIG. 3 is a side elevational view thereof, the opposite side being identical;

FIG. 4 is a left end elevational view thereof; and

FIG. 5 is a reduced scale perspective view thereof with a shaft and handle being shown in broken lines for illustrative purposes only.

The tool shaft is shown broken away in FIGS. 1-3 to depict indeterminate length.

FIG. 1

FIG. 2

FIG. 3

FIG. 4

FIG. 5
